(57) **CLAIM**

I claim the ornamental design for a toothpick holder, as shown and described.

DESCRIPTION

FIG. 1 is a perspective view of a toothpick holder, showing my new design;

FIG. 2 is a front elevational view thereof, the rear, left-side and right-side elevational views all being a mirror image thereof;

FIG. 3 is a top plan view thereof;

FIG. 4 is a bottom plan view thereof; and,

FIG. 5 is a cross-sectional view thereof, taken generally along lines 5—5 of FIG. 3.
